APPARATUS FOR USE IN REFINING OF LEAD BULLION AND SIMILAR OPERATIONS

Filed Feb. 9, 1927

Patented Oct. 9, 1928.

1,687,187

UNITED STATES PATENT OFFICE.

GEORGE KENNETH WILLIAMS, OF PORT PIRIE, SOUTH AUSTRALIA, AUSTRALIA.

APPARATUS FOR USE IN REFINING OF LEAD BULLION AND SIMILAR OPERATIONS.

Application filed February 9, 1927, Serial No. 166,987, and in Australia March 6, 1926.

This invention relates to certain improvements in apparatus for use in the refining of lead bullion and similar operations and refers more especially to apparatus for the refining of lead bullion containing other metals such as copper or gold or silver or mixtures thereof.

Though this invention is herein described as adapted and used for the refining of lead bullion it will be understood that it is also applicable to the treatment of other liquid systems wherein certain constituents or substances (sometimes in the form of "impurities") are removed by subjecting the same to differential temperatures.

This invention is especially adapted for the refining of lead bullion by such processes wherein zinc is incorporated with the said bullion for the formation of certain alloys of the said metals with zinc (with or without lead); such as the Parkes process wherein crusts are formed comprising alloys of the said metals with zinc (with or without lead); or processes for the enrichment of the said crusts contained in the aforesaid Parkes process or for the refining of bullion wherein a sufficient quantity of zinc is incorporated with the said crusts or the said bullion and the same is maintained at the required temperature for the formation of molten layers of conjugate solutions, the upper layer of which comprises an alloy with zinc of other metal or metals and the lower layer of bullion, which, if desired, can be cooled to its eutectic temperature producing residual bullion relatively low in such metals.

The invention is also applicable to the operation known as "liquation" as applied to the crusts formed by the aforesaid Parkes process in which the said crusts are heated for the removal of excess lead.

In addition the invention is applicable to the preliminary treatment to which lead bullion is usually subjected for the removal of the major portion of the copper contained therein, wherein the temperature of the liquid bullion is lowered causing the copper or compounds of copper to separate out due to the decreased solubility thereof in lead at such lower temperatures.

In the refining of bullion as at present practised, it is customary to maintain the said bullion in a molten condition in comparatively shallow open vessels known as kettles, which are set in the necessary brickwork,

having a flue or other means for heating and cooling the same around the bottom and the sides. In some cases reverberatory furnaces are used for certain treatment of lead bullion.

In the refining of bullion containing alloying metals, it is necessary that the bullion should be heated to a certain temperature and then either a portion thereof or the whole cooled to a certain temperature, and these open kettles being relatively broad and shallow do not well adapt themselves to these conditions, nor are the said kettles adapted for continuous treatment when relatively large tonnages are required. These objections also apply to reverberatory furnaces.

Now the object of this invention is to provide an apparatus for use in the refining of lead bullion and similar operations wherein the bullion or other material being treated is more effectively subjected to differential temperatures such apparatus being especially adapted for the refining of bullion or the enrichment of Parkes crusts by continuous treatment. By operating in an apparatus in accordance with this invention a continuous inflow of bullion may be maintained at the top and a continuous outflow of treated or residual bullion from the bottom and either a continuous or periodic removal of the crusts or conjugate solutions formed, comprising the alloy desired to be removed.

I accomplish these objects by providing a vessel within which a deep narrow column of molten metal may be maintained having means whereby different temperatures may be applied to different portions thereof.

The apparatus constructed in accordance with this invention comprises one or more deep narrow kettles—that is to say, kettles in which the dimensions are such that the depth is greater than the diameter in contra-distinction from the usual open shallow kettles which are usually approximately hemispherical in shape. The kettles may be of any convenient shape, that is to say, they may be circular or oval in cross section and may be either straight sided or tapering or "stepwise" that is, of differing diameters decreasing or increasing downwards. These kettles may be arranged as single units or in series in such manner that the metal may flow from the discharge of one to the feed

of the other when continuous treatment is desired. Means are provided for maintaining different portions of these kettles at differential temperatures—that is to say, a relatively high temperature at the top and a relatively low temperature at the bottom and in some cases—where the temperature of the bottom is at or about the eutectic of the metal therein—a slightly higher temperature at the discharge orifice than at the bottom. Any suitable means may be adopted for this purpose, such as an electrical heating medium, but for practical metallurgical purposes I prefer the mounting of the kettles in brickwork having suitable flues provided with burners for liquid or gaseous fuel so that any portion of the kettle may be heated to a relatively high temperature and another portion to a relatively low temperature by adjusting the burners at that portion or by circulating cool air around that portion if necessary.

In order that this invention may be more clearly understood reference may be had to the accompanying sheet of drawings wherein an apparatus is illustrated adapted more especially for the refining of lead bullion, though not confined thereto. In these drawings—

Figure 1 is a view in sectional elevation of an apparatus constructed and arranged in accordance with this invention.

Figure 2 is a plan view in section of a part of Figure 1 taken on the line 2—2.

Figure 3 is a plan view in section of a part of Figure 1 taken on the line 3—3.

Figures 4 and 5 are vertical sections of a portion of a kettle showing the accommodation of means for ensuring the admixture of the metals.

The apparatus embodying this invention preferably consists of one or more long narrow vessels 10 made of cast iron or other suitable material capable of resisting the necessary temperature to which they are subjected. Figure 1 illustrates a series of two of these kettles 10. These kettles are formed open at the top and are preferably provided with means for continuously or intermittently removing the molten metal from the bottom. For this purpose the said kettles may be provided either with a suitable tapping hole or with upwardly projecting spouts 13, the upper lips 14 of which are preferably below the upper rims of the kettles 10, and, if desired, these upwardly projecting spouts may be provided with a number of tapping outlets so that the height of the overflow lip thereof may be regulated and adjusted to suit requirements.

Means are provided for subjecting the said vessel to differential temperatures, such as by providing two or more circular or surrounding flues 11 and 12 around different portions of the kettle. These flues 11 and

12 are preferably independent, but may have communicating passages so that any desired temperature may be maintained at any particular point or portion of the said vessel. Inasmuch as it is desired that a high temperature be maintained in the upper portion of the kettle, the flue 11 surrounding that portion of the kettle is so designed that a high temperature may be maintained thereat and for this purpose a burner 15 for liquid or other fuel is provided. As at the lower portions of the kettle a relatively low temperature is usually required, such as the eutectic temperature of the residual bullion, the flue or flues 12 surrounding the lower portions of the kettle or vessel may, in addition to means for supplying heat thereto, such as a burner 16 having means for cooling the same, such as circulating cold air or water pipes, the said flues 12 being cut off from the main flues for the time being by means of a suitable damper. As in some operations the bullion, at the point of entry into the discharge orifice or spout 13, may be just at the eutectic temperature of the residual bullion, to prevent the same freezing and thus obstruct the continuous flow of the bullion, the said outflow pipe or spout 13 may be provided with an independent surrounding flue 17 having a burner 18 whereby heat may be applied thereto and a slightly higher temperature maintained within the said spout 13.

The kettle may be cast in one piece. However, as the upper portion of the kettle or vessel is maintained at a considerably higher temperature it is, therefore, more liable to deterioration and cracking. I therefore preferably form the vessel in two or more parts having flanges 19 and 20 by which the parts may be bolted or fastened together, so that the upper portion may be renewed from time to time without having to dismantle or discard the lower portion. For the purpose of maintaining a relatively metal-tight joint the two flanges 19 and 20 are preferably formed with a circular or concentric groove 21 within which a circulating water pipe 22 is accommodated, so that any metal entering the said joint is frozen and leakage avoided, or suitable packing may be provided in the groove 21.

In order that the temperature of the bullion at the lower end of the column may be accurately determined the kettles 10 are preferably provided with inclined pipes or tubes 10' adapted to accommodate suitable pyrometer couples.

By means of a kettle of this description the refining of lead bullion containing alloying metals may be effected as a continuous operation, the bullion being fed into the open mouth at the top together with such amount of zinc as may be necessary for the

formation of the particular alloy required, the residual bullion being allowed to overflow continuously from the spot 13 whilst the alloy formed may be removed either continuously or periodically from the upper portion of the kettle in the form of crusts or conjugate solution according to the nature of the operation.

The drawings illustrate one particular adaptation of the invention wherein the bullion to be purified is passed through two kettles arranged in series but it will be obvious to anyone skilled in the art that the kettles may be used independently or the kettles may be arranged in various ways.

For example alloys of certain metals may be preferentially removed in the first kettle and the bullion discharged therefrom and passed to the second kettle in which alloys of other metals may be removed and if necessary through further kettles until the residual bullion discharged from the last kettle is relatively free from such metals.

In Figure 1, I have shown a series of two kettles 10 so arranged that the discharge spout 13 of the upper kettle delivers into the top of the lower kettle. Such an arrangement is especially adapted for continuous treatment of bullion for the differential removal of alloying metals contained therein. In such treatment the bullion is continuously fed into the top of the upper kettle where a requisite amount of zinc is incorporated and the requisite degree of heat maintained for the formation of a conjugate solution comprising an alloy relatively high in certain metal or metals. The lower portion of this upper kettle is maintained at such a temperature that the bullion discharging from the spout 13 and delivered into the top of the lower kettle is relatively low in such metals. The bullion discharging into the top of the lower kettle is incorporated with the requisite amount of zinc and the temperature is maintained thereat at the requisite degree for the formation of a conjugate solution relatively high in the remaining alloying metal or metals. By maintaining the lower portion of the second kettle at a temperature just above the eutectic of the residual bullion and the temperature of the spout 13 just above that temperature residual bullion relatively low in all the metals may be discharged from the spout of the second kettle. The alloys or crusts formed in the upper portions of the two kettles may be removed either continuously or periodically as may be required.

When the incorporation of the zinc with the bullion in the upper portion of the kettle is effected by causing the said bullion to pass down through a layer of molten zinc (or an alloy high in zinc) means may be provided for ensuring complete admixtures and for this purpose a rotating stirrer 23 mounted on

a spindle 24 accommodated within a cylinder 25 may be provided as shown in Figure 4 or alternatively baffle plates or trays 26 having staggered openings may be provided as shown in Figure 5. These trays or baffle plates may be mounted upon a vertical shaft 27 so that they may be moved or adjusted in height or position as required in the operation.

By means of a kettle of this description the treatment of crusts obtained in the Parkes process for the purpose of enriching the same may be effected as a continuous operation, the crusts being fed into the open mouth at the top and the bullion which separates from such crusts being allowed to discharge from the bottom of the kettle through the spout 13. During its passage down the kettle this bullion is either cooled to its eutectic temperature, or any other desired temperature according to the treatment, while the enriched product may be removed either periodically or continuously, as may be desired, in the form of crusts, or of conjugate solutions, or of a mixture of conjugate solution and dross or crusts, according to the quantity of infusible material present in the crusts treated and the degree of temperature maintained in the upper portion of the kettle.

The operation of refining lead bullion in an apparatus of this description may be effected in an exceedingly simple and efficient manner, with a saving in operating costs as compared with the kettles as at present in use.

This invention is also adapted for the preliminary treatment of lead bullion for the separation of copper (which is usually effected in reverberatory furnaces) prior to refining in which the bullion at a relatively high temperature is cooled to a relatively low temperature causing copper or compounds of copper to separate out due to their being less soluble in lead at such lower temperature.

The invention is also adaptable for the treatment of other metals or substances than lead bullion by methods which involve the maintenance of a liquid system and subjecting the same to differential temperatures for the separation or removal of other metals or compounds contained therein.

I claim:—

1. An apparatus for use in the refining of lead bullion and similar operations comprising a vessel within which a deep narrow column of molten material may be maintained having means whereby different temperatures may be applied at different portions thereof and means for independently withdrawing products from at or about the top and at or about the bottom thereof.

2. An apparatus for use in the refining of lead bullion and similar operations com-

prising a deep narrow kettle having a plurality of flues surrounding different portions thereof at varying heights with means for maintaining different temperatures in the 5 said flues and means for independently withdrawing products from at or about the top and at or about the bottom thereof.

3. An apparatus for use in the refining of lead bullion and similar operations comprising a deep narrow kettle mounted in suitable brickwork having a series of flues surrounding different portions thereof with means for maintaining different temperatures in the said flues and means for removing 10 the molten metal from the lower portion of the said kettle.

4. An apparatus for use in the refining of lead bullion and similar operations comprising a deep narrow kettle having means 15 for applying different temperatures to different portions thereof a discharge spout leading from the bottom of the said kettle, the upper lip of which is at a lower level than the upper rim of the said kettle and 20 means for maintaining said spout at the requisite temperature.

5. An apparatus for use in the refining of lead bullion and similar operations comprising a deep narrow kettle mounted in suitable brickwork having an upper flue surrounding the upper portion thereof, a burner arranged within the said flue for heating that portion of the kettle surrounded thereby, a lower flue surrounding the lower portion 30 of the kettle having means for maintaining the same at the requisite temperature, a discharge spout leading from the bottom of the said kettle and a separate flue surrounding the said discharge spout 35 having means for maintaining the said spout at the requisite temperature.

6. An apparatus for use in the refining of lead bullion and similar operations comprising the combination with a deep narrow 40 kettle having means for maintaining the same at different temperatures at different portions thereof, of means for effecting 45

the admixture of the bullion or other material passing therethrough.

7. An apparatus for use in the refining of 50 bullion and similar operations comprising the combination with a deep narrow kettle having means for maintaining the same at different temperatures at different portions thereof, of a series of baffle plates or 55 trays having staggered openings mounted in the upper portion of the said kettle for effecting the admixture of the bullion or other material passing therethrough.

8. An apparatus for use in the refining of 60 lead bullion and similar operations comprising a deep narrow kettle made in two sections formed with flanges by which the said two sections may be bolted together, the said flanges having a groove or channel 65 within which a cooling medium may be accommodated for maintaining a liquid-tight joint, means for applying a relatively high temperature to the said upper portion and means for maintaining a relatively low 70 temperature to the said lower portion of the kettle and a discharge spout leading from the bottom of the said kettle having means for maintaining the said spout at the desired 75 temperature.

9. An apparatus for use in the refining of 80 lead bullion and similar operations comprising a number of kettles mounted in suitable brickwork and arranged in series in such a manner that the discharge of one is 85 delivered into the feed of the other except the last in the series, said brickwork having separate flues arranged in such a manner that the upper portions of the said kettles are maintained at a relatively high temperature and the lower portion of the said kettle at a relatively low temperature, each kettle having a discharge spout adapted to deliver the metal from the bottom thereof with 90 means for maintaining the said spouts at the temperatures required.

In witness whereof I hereunto affix my signature.

GEORGE KENNETH WILLIAMS.
